By Derby Gregory *attys.*

UNITED STATES PATENT OFFICE.

ARTHUR J. HOWARD, OF MALDEN, MASSACHUSETTS, ASSIGNOR TO THE
WIRE GRIP FASTENING COMPANY, OF CHICAGO, ILLINOIS.

DESIGN FOR A NAIL OR SLUG.

SPECIFICATION forming part of Design No. 24,757, dated October 15, 1895.

Application filed September 9, 1895. Serial No. 562,007. Term of patent 14 years.

To all whom it may concern:

Be it known that I, ARTHUR J. HOWARD, of Malden, in the county of Middlesex and State of Massachusetts, have invented and produced 5 a certain new and useful Design for a Nail or Slug, of which the following is a specification, reference being had to the accompanying drawings, forming a part thereof.

Figure 1 of the drawings is an isometric view 10 of a nail or slug, showing my design; and Fig. 2 is an end view thereof.

The leading feature of my design for nails or slugs used for ornamenting boot or shoe heels consists in the rounded longitudinal 15 edges of a nail or slug connected by a flat web portion.

In the drawings the rounded longitudinal edges *a* of the nail or slug are connected by a thinner web-like portion *b*, having its opposite faces parallel and quadrilateral in shape. 20

I claim—

The design for a nail or slug, substantially as set forth.

In testimony whereof I have signed my name to this specification in the presence of 25 two subscribing witnesses.

ARTHUR J. HOWARD.

Witnesses:

JOHN C. EDWARDS,
ALEX. C. PROUDFIT.
